UNITED STATES PATENT OFFICE.

JULIUS MILLER AND CHARLYS M. HANSEN, OF YOUNGSTOWN, OHIO.

AUTOMATIC CUT-OFF.

No. 910,939.

Specification of Letters Patent.

Patented Jan. 26, 1909.

Application filed February 7, 1908, Serial No. 414,814. Renewed October 23, 1908. Serial No. 459,213.

To all whom it may concern:

Be it known that we, JULIUS MILLER and CHARLYS M. HANSEN, citizens of the United States, residing at Youngstown, in the county 5 of Mahoning and State of Ohio, have invented certain new and useful Improvements in Automatic Cut-Offs; and we do hereby declare the following to be a full, clear, and exact description of the invention, such as will 10 enable others skilled in the art to which it appertains to make and use the same.

Our invention relates to new and useful improvements in automatic cut-offs and more particularly to that class adapted to be 15 used in connection with gas mains and our object is to provide means for automatically closing the feed pipe from the gas main when the pressure on the gas is decreased to a certain degree.

20 A further object is to provide means for adjusting the stroke of parts of the device and a still further object is to provide means for opening the cut-off when desired.

Other objects and advantages will be hereinafter referred to and more particularly 25 pointed out in the claims.

In the accompanying drawings which are made a part of this application, Figure 1 is a 30 sectional view through a portion of a feed pipe showing our improved cut-off mechanism applied thereto. Fig. 2 is a sectional view as seen on line 2—2, Fig. 1. Fig. 3 is a sectional view as seen on line 3—3, Fig. 1, and, Fig. 4 is a detail, sectional view as seen on 35 line 4—4, Fig. 1.

Referring to the drawings in which similar reference numerals designate corresponding parts throughout the several views, 1 indicates a casing, one face of which is provided 40 with a removable cover 2, said cover being arranged to hold a glass 3 or other transparent substance whereby the interior of the casing may be readily observed without removing the cover.

45 Located in the bottom of the casing 1, is a conduit 4, into the ends of which are introduced sections 5 and 6 of a feed pipe, said pipe being of that class commonly employed for conveying gas, or the like, from the street 50 mains into a building, the section 5 being interposed between the main and the conduit, while the section 6 extends from the opposite end of the conduit to any preferred point in the building.

55 The conduit 4 is divided into compart-

ments by means of a wall 7, which is preferably located adjacent its longitudinal center, so that the product in passing through the conduit will be caused to flow through a chamber 8 on the upper wall of the conduit, 60 the chamber 8 being placed in communication with the two sections of the conduit through the medium of ports 9 and 10, the port 9 being surrounded by a conical seat 11, with which is adapted to coöperate a conical valve 12, said valve being so arranged that when properly seated in the conical seat, the flow of the product will be entirely cut off.

When the product is flowing through the conduit, the valve 12 is suspended in the conduit and is supported by means of a shaft 13, said shaft extending upwardly through the wall of the chamber 8 and has pivotally secured to its upper end a rack bar 14, said rack bar being held in a vertical position at 70 all times by means of a slotted keeper 15 carried at the upper end of a standard 16, the lower end of the standard being threaded into a seat on the upper wall of the chamber 8, the stroke of the shaft being limited by 75 means of a collar 17, surrounding the shaft 13 above the wall of the chamber 8, said collar being held in its adjusted position on the shaft by means of a set-screw 18, the collar when engaging the upper wall of the chamber 85 18, stopping the downward movement of the shaft.

The peripheral face of the valve 12 is provided with a plurality of encircling channels 19, in which are adapted to be disposed packing rings 20, thereby positively closing the port 9 when the valve is properly seated and the valve is loosely held on the end of the shaft 13 so that it may properly adjust itself in its seat by providing a ball 21 on the lower 95 end of the shaft and entering the same in a socket 22 in the valve 12, said valve being provided with a longitudinal bore 23, through which the shaft extends, said bore being slightly larger than the shaft, thereby 100 permitting the valve to yield and the valve is held in position on the shaft by threading a plug 24 into the lower end of the opening 23, the inner end of the plug being concave to fit the contour of the ball 21, said plug forming a part of the socket for the ball.

Extending upwardly from the wall of the chamber 8, is a stem 25, on which is adjustably mounted a sleeve 26, said sleeve being held in its adjusted position on the stem by 110

means of a binding screw 27, the upper end of the sleeve being provided with ears 28, between which is pivotally mounted a frame 29, one end of the frame being provided with 5 a toothed rack 30, which is adapted to mesh with the rack bar 14 and raise and lower the valve 12 when the frame is rocked on its pivot point. The frame 29 is pivoted at one end between the ears 28, so that the major 10 portion of the frame extends to one side of the pivot point and said frame is provided with a longitudinal slot 31, in which is adapted to travel a balance weight 32, said weight being globular and held in the slot by 15 forming the walls 33 of the slot V-shaped, as best shown in Fig. 2 of the drawings.

The frame 29 normally rests at an angle to the vertical axis of the stem 25, so that the weight 32 will normally rest adjacent the 20 pivoted end of the frame and said frame is held in this position by the pressure of the fluid passing through the conduit acting on a piston 34 mounted in a cylinder 35, which cylinder communicates with the interior of 25 the chamber 8 and preferably immediately over the port 10, the piston being attached to the frame 29 by means of links 36, which are pivoted at their lower ends to an ear 37 on the piston 34 and at their upper ends to an 30 ear 38, on the frame 29 and it will be readily seen that as long as the pressure in the chamber 8 is sufficient to retain the piston 34 at the upper end of the cylinder 35, the valve 12 will be retained in its lowered position and 35 the fluid permitted to freely flow through the ports 9 and 10. As soon, however, as the pressure in the chamber has been reduced to a certain degree, the weight of the frame will move the piston 34 downwardly and elevate 40 the valve through the medium of the rack bar 14 and toothed rack 30 and it will further be seen that when the frame has been lowered slightly below the horizontal, the balance weight 32 will be moved to the opposite 45 end of the frame 29 and the added weight overcome the remaining pressure in the chamber and positively seat the valve 12 in its seat 11, thereby completely stopping the flow of the fluid through the conduit. The 50 descent of the frame 29 is further regulated by means of a sliding weight 39, which is located adjacent the outer end of the frame 29 and is adjustably secured to a rib 40 on the upper face of the frame 29, the weight being 55 held in its adjusted position on the rib by means of a set screw 41 and it will be readily seen that as the weight 39 is moved towards the outer end of the rib, the valve will close against a greater pressure in the chamber 60 than when the weight is nearer the inner end of the rib.

This device is adapted more particularly to be used in connection with gas when used as fuel and illumination and as gas burners 65 are frequently left burning during the night,

the reduction of the flow of gas to a certain degree will extinguish the light and if the pressure is renewed, the room becomes filled with the gas and unless discovered in time, will asphyxiate anyone sleeping in the room, 70 while with the use of our automatic cut-off, when the pressure of the gas has been reduced to a certain degree, the valve will be seated and the flow of gas completely stopped until the parts of the cut-off are manually 75 operated to again open the valve and if the pressure of the gas has been increased to a sufficient degree, the piston 34 will be held in its elevated position and the gas permitted to flow uninterruptedly until the pressure is 80 again reduced.

The valve 12 is entered into the conduit 4 through an opening 41^a in the bottom of the conduit, said opening being surrounded by a collar 42, which is exteriorly threaded to receive a cap 43, the opening 41^a being of sufficient diameter to loosely receive the valve 12 and permit said valve to be introduced into the conduit.

In regulating the distance to which the 90 valve will be required to move in order to engage its seat 11, the collar 17 is moved longitudinally on the shaft 13 and by lowering the collar on the shaft, the valve will be held in closer proximity to its seat, thereby requiring 95 a shorter stroke of the frame to close the valve and to further assist the escape of the gas through the port 9, the wall of the conical seat is provided with a plurality of openings 44, through which the gas may escape, as well 100 as at the upper end of the seat.

As the parts of the cut-off are inclosed in the casing 1, we provide means for mutually opening the valve 12 by pivotally mounting a lever 45 at one end of the casing, one end of the lever extending within the casing and the opposite end thereof into an inclosure 46, the inner end of said lever being weighted, as best shown at 47 in Fig. 1 and provided with a curved terminal 48, which is adapted to engage a curved finger 49 at the free end of the frame 29, whereby when the outer end of the lever 45 is depressed, the curved terminal will engage the finger and elevate the frame 29, thereby causing the balance weight 32 to 110 move to the pivoted end of the frame and at the same time lower the valve 12, and if the pressure of the gas in the conduit is sufficient to hold the piston 34 at the upper end of the cylinder 35, the gas may flow through the 115 ports uninterruptedly.

The outer end of the lever 45 is depressed through the medium of a plunger 50, said plunger extending upwardly through a stuffing box 51 at the upper end of the closure 46, 125 while the lower end thereof is pivotally secured to the lever 45 by introducing a pin 52 through the end of the plunger and through a slot 53 in the end of the lever.

Located within the casing 1 and in position 130

to be observed through the glass 3, is a gage 54, which may be of the usual or any preferred construction to indicate the amount of pressure in the feed pipe, said gage being 5 connected to the conduit 4 through a pipe 55, that portion of the pipe between the gage and conduit having a cock 56 therein, by which means the gas may be shut off from the gage when desired, and as the gage is located be- 10 tween the valve and the gas main, it can be instantly seen when the gas has reached the proper pressure, thereby obviating the necessity of tilting the frame 29 when the pressure of the gas is not sufficient to hold the frame in 15 its elevated position.

It will thus be seen that we have provided a cheap and efficient device for automatically cutting off the flow of gas in one direction when the pressure of the gas has become 20 weakened to a certain degree and that the flow of gas will be prevented until the parts of the cut-off are manually operated to open the same. It will further be seen that the several parts of the device may be readily 25 adjusted to increase or decrease the stroke of the several parts thereof, thereby causing the cut-off to operate under various pressures.

What we claim is:

30 1. The herein described automatic cut-off, comprising a conduit divided into compartments by means of a stationary wall and having a port at each side of said wall, a chamber connecting said ports, a valve adapted to close one of said ports and means having movable weights thereon adapted to automatically operate the valve when the pressure in the chamber is reduced.

2. In an automatic cut-off, the combination 40 with a conduit having a dividing wall, a port at each side of said wall, a chamber connecting said ports, a conical seat surrounding one of said ports open at both ends, a valve adapted to be entered in said seat 45 and close communication between the two ends of the conduit; of means to automatically move said valve into engagement with the seat when pressure in the chamber is reduced.

50 3. An automatic cut-off, comprising the combination with a conduit, a wall dividing said conduit into compartments, each compartment having a port and means to convey gas into said conduit; of a chamber 55 adapted to form communication between said ports, a seat surrounding one of said ports, a valve adapted to be seated in said seat and the flow of gas through the ports stopped, a shaft carrying said valve, a cylinder 60 at one end of said chamber, a piston in said cylinder and means having movable weights thereon interposed between said piston and shaft to operate the valve when the piston is lowered.

65 4. In an automatic cut-off, the combina-

tion with a conduit having ports therein, a division wall between said ports, a valve seat surrounding one of said ports and means to convey gas into said conduit; of a chamber communicating with said ports, a shaft 70 extending through the chamber and through the port having the seat, a valve loosely mounted on the lower end of said shaft, means to limit the stroke of said shaft and additional means to automatically raise the 75 valve and dispose the same in its seat when the pressure in the chamber has been reduced.

5. In an automatic cut-off, the combination with a conduit having ports therein, a division wall between said ports, a chamber 80 forming a passage between said ports, a valve adapted to close one of said ports, a shaft carrying said valve, a frame pivotally mounted upon said chamber, means at one end of said frame to raise and lower said 85 shaft and means controlled by the pressure in the chamber adapted to support the frame in its elevated position, whereby the valve will be held in its lowered position.

6. In an automatic cut-off, the combination with a conduit having ports therein, a seat surrounding one of said ports and a valve adapted to be moved into said seat; of a shaft supporting said valve, a rack bar at the upper end of said shaft, a frame having 95 a longitudinal slot therein, means to pivotally support said frame, a rack carried by said frame adapted to engage the rack bar on the shaft and means to normally support said frame in an elevated position. 100

7. In an automatic cut-off, the combination with a conduit, a valve seat in said conduit, a valve adapted to be engaged with said seat, a shaft supporting said valve, a pivoted frame adapted to engage the upper 105 end of the shaft and seat the valve, a pivoted lever adapted to engage one end of the frame and elevate the same, an inclosure for the outer end of said lever and a plunger pivoted to the lever adapted to operate the 110 same when pressure is applied thereon.

8. The combination with a valve and a seat therefor; of a shaft loosely attached to said valve, means to limit the stroke of said shaft, a rack bar at the upper end of said shaft, a sleeve, ears at the upper end of said sleeve, a supporting stem for said sleeve, a frame pivotally mounted between said ears and having a longitudinal slot therethrough, a balance weight in said slot adapted to move 115 to opposite ends of the frame when the frame is raised and lowered, a rack carried by the frame adapted to engage the rack bar on the shaft and operate the valve when the frame is rocked and pressure-operated means to 120 hold the frame in its elevated position.

9. In an automatic cut-off, the combination with a conduit, a valve in said conduit, means to automatically operate said valve to close communication through the con- 130

duit and a pressure gage communicating with said conduit; of a casing inclosing said conduit, valve-operating mechanism, and gage and means to manually operate the valve-operating mechanism, whereby the valve will be lowered and communication through the conduit restored.

In testimony whereof we have signed our

names to this specification in the presence of two subscribing witnesses.
